DUPLICATOR

Leo R. Starr, Chatham, Ontario, Canada

Application March 16, 1938, Serial No. 196,245

5 Claims. (Cl. 101—133)

This invention relates to duplicators and the object of the invention is to provide a duplicator having a semi-cylindrical gelatin coated surface for producing copies and having a roller movable 5 through an arc to travel over the semi-cylindrical surface in obtaining an imprint.

One of the particular objects of the invention is to provide a semi-cylindrical or arcuate table over which a flexible gelatin coated sheet is positioned, said sheet being held at one edge and means being provided for placing a tension on the other edge of said sheet to stretch the sheet into firm contact with the semicylindrical table.

Another object of the invention is to provide a 15 duplicator provided with end plates and having a semi-cylindrical table mounted between the end plates and a U-shaped roller frame pivotally mounted on the axis of the semi-cylindrical table and turnable thereover to press the duplicating 20 paper into contact with the printing surface.

A further object of the invention is to provide a semi-cylindrical table having a flange at one edge over which the gelatin coated flexible sheet may be engaged and having a pivoted arm adjacent the opposite edge of the semi-cylindrical table over which the opposite edge of the said strip is engaged and spring means tending to turn the said arm on its pivot to stretch the gelatin coated flexible sheet tightly over the semi-cylindrical table.

Another object of the invention is to provide a cam operated means for raising the tension member against the tension of the spring means to allow removal of the gelatin coated flexible sheet.

These objects and the several novel features of the invention are hereinafter more fully described and claimed and the preferred form of construction by which these objects are attained is shown in the accompanying drawing in which—

Fig. 1 is a plan view of a duplicator embodying my invention.

Fig. 2 is an end view thereof taken from the right end of Fig. 1.

Fig. 3 is a section taken on line 3—3 of Fig. 1.

Fig. 4 is an enlarged section taken on line 4—4 of Fig. 2.

Fig. 5 is an enlarged edge view of the gelatin coated flexible sheet for engagement over the semi-cylindrical table.

The device comprises a pair of semi-circular end members 1 and 2 shown in Figs. 1, 2 and 3. These end members are cast and are each provided with a thickened rim portion 3 as shown in Fig. 3. The table is a semi-circular sheet metal plate 4 which fits in grooves in the portions

3 of the opposite end plates and the end plates are connected together by a series of three bolts 5 shown in Figs. 1, 2 and 3. The sheet metal table is provided with an inturned flange 6 shown more particularly at the left of Fig. 3 and the duplicating surface comprises a semi-flexible sheet 7 shown more particularly in Fig. 5 having a gelatin coating on the outer face or surface 8. Secured to one edge of the sheet 7 is a channel member 9 while a similar channel member 10 is secured to the opposite edge of the sheet.

In applying the sheet to the sheet metal table, the channel 9 is hooked over the flange 6 at the edge of the sheet metal table and the flexible sheet is laid over the table so that the channel member 10 hangs below the inturned edge 11 of the table opposite the flange 6.

A U-shaped tension member 12 having a cross-bar 14 is pivotally mounted on the rod or bolt 5 at the left of Fig. 3 and the cross-bar 14 may be engaged in the channel member 10 at the edge of the sheet 7. Springs 15 are provided for the arms 12 at the opposite ends of the cross-bar 14 and these springs are connected to the end plates 1 and 2 to pull the crossbar 14 downwardly and place a tension on the sheet 7 to hold it in firm contact with the semi-cylindrical table. As the outer surface 8 of the flexible sheet 7 is coated with gelatin, this provides a firm gelatin face for the duplicator.

In order to raise the crossbar 14 against the tension of the springs 15, a shaft 16 extends between the end plates and a cam 17 is mounted on the shaft 16 for each end arm 12. In the position shown in Fig. 3, the cam is turned to allow clearance between the cams and the arms 12 to allow the full tension of the springs 15 to be applied to the sheet. In order to release the sheet, a lever 18 is secured to one end of the shaft 16 and this lever is mounted in a recess 19 in the end plate 1. By turning this lever 18 in a counter-clockwise direction in the recess 19 the cams 17 are turned to raise the arms 12 and crossbar 14 out of the channel member 10, at which time, by swinging the channel member 10 outwardly the flexible sheet 7 may be lifted off from the semi-cylindrical table and disengaged from the flange 6. This arrangement is provided so that the flexible strip containing the gelatin surface may be removed from the device and wrapped up when not in use to prevent the gelatin face from drying out.

The end plates are each provided with an internal boss 20 and a U-shaped roller carrying frame 21 is provided which is pivotally mounted

on the end plates by means of the screws 22 extending into the bosses 20. This frame comprising the end arms 21 is provided with a crossbar 23 to which the handle 24 is connected and a soft rubber roller 25 is provided having a shaft 26 extending into slots 27 in the end arms 21. A block 28 is secured in each end of the U-shaped frame by means of the screws 29 shown in Figs. 2 and 4 and each block carries a coiled spring 30 having a shoe 31 riding in contact with the shaft 26 and tending to press the same toward the axis of rotation of the roll carrier frame which is the center of the bosses 20. In the position shown in full lines in Fig. 3, these springs 30 press the shaft ends 26 to the bottom of the slots 27 and the crossbar 23 in this position rests on the rubber bumpers 32 carried on extensions 33 of the end plates. In order to operate the device, a paper sheet 34 is provided which is laid against the gelatin surface 25 at the edge 35 to position the same on the duplicator. After this edge has been positioned, the handle 24 is raised causing the roller 25 to roll over the sheet and as this roller is moved to the position shown in dotted lines at the right of Fig. 3 the sheet is rolled in firm contact with the gelatin surface on the flexible sheet 7. Upon completion of this rolling movement the handle 24 is returned to the position shown in full lines in Fig. 3 against the rubber stops 32, at which time, the paper sheet 34 may be removed from the gelatin surface and the sheet will be printed in accordance with the printing on the gelatin surface.

As hereinbefore described, the lever 18 may be turned in a counter-clockwise direction in the recess 19 to turn the cams 17 and raise the crossbar 14 out of the channel 10 at the edge of the flexible sheet 7 and allow removal of the sheet. To replace the flexible sheet 7 the channel 9 is engaged over the flange 6 of the semi-cylindrical table and the sheet is laid over the table and the channel 10 is brought beneath the crossbar 14 of the tensioning device. At this time, the handle 18 may be returned to the position shown in full lines in Fig. 2 and the cams will be turned to the position shown in full lines in Fig. 3 thus allowing the springs 15 to pull the crossbar 14 down into the channel 10 and maintain a tension on the sheet. It will be noted that the handle 18 is movable in a recess 19 in the end plate 1. This is done so that the end arms 21 of the roll carrier frame will clear the handle when turned to the opposite side of the device.

From the foregoing description it becomes evident that the device is very simple and efficient in operation, will maintain an even tension on the gelatin coated sheet and will also maintain an even pressure on the paper sheet due to the springs 30, will allow removal or replacement of the gelatin coated sheet and provides a device which accomplishes the objects described.

Having thus fully described my invention, its utility and mode of operation, what I claim and desire to secure by Letters Patent of the United States is—

1. In a duplicator, a stationary semi-cylindrical table provided with end plates, a frame pivoted on the end plates and turnable over the cylindrical casing, a pressure roller carried by the frame, rubber stop means for the frame carried by the end plates, a flexible sheet provided with a gelatin coating, a channel at each edge of the flexible sheet, one channel being engaged over one edge of the semi-cylindrical table and the sheet ex-

tending over the surface of the semi-cylindrical casing, a U-shaped frame pivotally mounted within the casing, the frame being provided with a crossbar engaging in the other channel of the flexible sheet, a spring tending to turn said frame on its pivot to apply tension to the flexible sheet, cam means for raising the U-shaped frame against the tension of the spring and means operable from the exterior of the table for turning the cam means.

2. In a duplicator, a pair of end plates, a stationary semi-cylindrical table secured between the end plates, a flexible sheet provided with a gelatin coating, a channel at each edge of the flexible sheet, one channel being engaged over the edge of the semi-cylindrical casing, a crossbar arranged for engagement in the other channel, a pair of pivoted arms supporting the crossbar, a spring for each pivoted arm tending to pull the same down and place a tension on the flexible sheet, a shaft extending between the end plates, a cam on the shaft for each pivoted arm, a lever for turning the shaft from the exterior of the casing, the arrangement being such that as the shaft is turned the cams will move the pivoted arms against the tension of the springs to disengage the crossbar from its channel on the flexible sheet.

3. In a duplicator, a stationary semi-cylindrical casing provided with end plates, a U-shaped frame member pivotally supported in the end plates on the axis of the semi-cylindrical casing, a gelatin coated flexible sheet positioned on the semi-cylindrical casing, one edge of the sheet being anchored to the casing, means for applying a tension to the opposite edge of the sheet to maintain the same in tight contact with the semi-cylindrical casing, a pressure roller carried by the U-shaped frame member and movable over the casing by turning the frame member, each end plate being provided with an extension and a rubber cushion on each extension engaged by the U-shaped frame member as it is turned to one end of its path of travel.

4. In a duplicator, a semi-cylindrical sheet metal table, supporting means therefor, a gelatin coated flexible sheet having one end detachably secured to an edge of the table, tensioning means for the other end of the sheet adjacent the opposite edge of the table, an arm pivoted to the axis of the table, a roller carried by the arm and movable across the gelatin sheet, said supporting means terminating in a horizontal plane on the opposite side of the pivot point from that occupied by the table and adapted to support the device in stationary position on a plane surface for the printing operation by the roller.

5. In a duplicator, a semi-cylindrical sheet metal table, a gelatin coated flexible sheet having one end detachably secured to an edge of the table, tensioning means for the other end of the sheet adjacent the opposite edge of the table, an arm pivoted at the axis of the table, a roller carried by the arm and movable across the gelatin sheet, a supporting means for the semi-cylindrical table terminating in a plane on the opposite side of the axis from that occupied by the semi-cylindrical sheet and providing a means for supporting the table in a stationary position, the roller being mounted on the arm in a manner to permit limited radial movement, and spring means resisting radial movement of the roller.
